(57) **CLAIM**

The ornamental design for the display screen with animated graphical user interface for smart home automation system having a multifunction status, as shown and described.

DESCRIPTION

FIG. 1 is a front view of a display screen with animated graphical user interface for smart home automation system having a multifunction status showing our new design; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; FIG. 7 is a front view of a seventh image thereof; and, FIG. 8 is a front view of an eighth image thereof. The broken lines illustrate portions of the display screen with animated graphical user interface for smart home automation system having a multifunction status that form no part of the claimed design. The appearance of the animated images transitions between the images shown in FIGS. 1-8. The process, sequence, or period in which one image transitions to another forms no part of the claimed design.
